KENNETH E. LATIMER, OF ALDWYCH, LONDON, ENGLAND, ASSIGNOR TO WESTERN ELECTRIC COMPANY, INCORPORATED, OF NEW YORK, N. Y., A CORPORATION OF NEW YORK

METHOD OF AND MEANS FOR REDUCING CROSSTALK IN CABLE SYSTEMS

Application filed January 13, 1932, Serial No. 586,263, and in Great Britain January 5, 1931.

This invention relates to telephone transmission systems and more particularly long distance telephone cables using voice frequency circuits worked on a four-wire basis or carrier frequency circuits, but is also applicable to open wire lines. The invention has for its primary object the reduction of crosstalk, but there are also other objects which will become apparent in the course of the explanation which follows.

It is well known that the near end crosstalk between two circuits in a cable varies in a very irregular manner as a function of the frequency, the irregularities arising from the fact that different phase shifts are associated with the capacity unbalances occurring at different points of the cable, so that at certain frequencies, groups of these unbalances will add up to give a high crosstalk, whereas at a slightly different frequency the phase relations will be such that this condition no longer holds. It is for this reason extremely difficult to reduce the near end crosstalk of an installed cable by means of networks connected between the circuits at one or both ends; in fact, for such an attempt to be successful it is necessary to have available a delay network or its equivalent, the phase shift of which is utilized to simulate the phase characteristics associated with the individual unbalances of the actual cable. The individual unbalances themselves must also be simulated and the whole network must then be applied between two circuits in such a way that crosstalk currents tend mutually to subtract. Naturally, such a process is difficult and cumbersome to such an extent that it is almost impracticable. For this reason any attempt to reduce near end crosstalk must necessarily be undertaken upon lengths of cable short compared with wave length e. g. loading sections.

Much the same considerations apply also with regard to far end crosstalk if there is a difference of velocity between the various circuits in the cable, e. g. between side and phantom circuits. Attempts have been made to reduce the far end crosstalk on installed cables by a process known as "poling" which consists of choosing one of the eight possible

methods of splicing a quad so that the phantom to side and side to side crosstalk may be reduced to a minimum. This process is usually carried out at one splice in the center of each repeater section and is applied to the reduction of phantom to side and side to side far end crosstalk, a reduction in the order of 30% being thereby obtained.

This particular method is not a very scientific one in that the crosstalks occurring upon either side of the poling point can not be selected to neutralize one another with any degree of precision, partly on account of differences in phase and attenuation and partly because the only known means of carrying out the selection is by trial and error, which is not very effective. With existing methods, when differences of attenuation occur between side and phantom circuits, either the phantom to side crosstalk has been reduced without reducing the side to phantom crosstalk, or vice versa, unless the tests are conducted on comparatively short lengths of cable. No precautions have hitherto been taken to secure exact equality of velocity among the various circuits.

According to a feature of the invention far end crosstalk between two circuits whose transmission times are substantially equal is corrected by the addition of condensers, inductances or resistances separated, by distances long compared with a wave length, from the unbalances which they correct, and adjusted to balance the crosstalk for either direction of transmission and with either of a pair of circuits considered as the disturbing circuit.

According to another feature of the present invention the balancing of far end crosstalk on lengths of cable long compared with a wave length in which the above condition of substantially equal velocities is not in the first place satisfactorily met is made more practicable and efficient by making the transmission times (and cut-off frequencies in the case of Pupin loading) substantially equal on all circuits in a group whether they be side circuits or phantom circuits, and whether or not a difference of attenuation will be produced by so doing, so that the far end

crosstalk becomes a simple function of frequency and so that a reduction in the crosstalk may be effected by use of simple devices, such as condensers or mutual inductances, connected to the ends or other points of the circuits. The methods by which this is done are described below.

According to another feature of the invention means are provided for making the terminal impedance presented by the equipment match the impedance of the line to a sufficient extent to enable the balancing to be carried out by means of condensers or other simple devices connected between the circuits whose crosstalk is to be reduced, such balancing devices being applied to lengths of cable long compared with a wave length.

According to another feature of the invention means are provided to enable the magnitudes of said balancing condensers to be determined by a series of simple measurements, even in the case in which the two circuits differ in attenuations. These and other features will become apparent from the description below.

According to another feature of the invention, a communication cable comprising conductors in groups forming four-wire circuits and two-wire circuits has the conductors for the four-wire circuits situated inside the conductors for the two-wire circuits. The increase in babble and crosstalk on the four-wire circuits, brought about by this change from the present normal arrangement, is removed by the methods hereinafter described and certain advantages are thereby secured.

According to another feature of the invention, a quadded cable is balanced for far end crosstalk by condensers associated with the various terminals of the phantom repeating coil groups.

The invention will be better understood from the following detailed description thereof when read in connection with the accompanying drawing in which:

Figs. 1 and 2 are diagrams employed to aid in a mathematical explanation of the invention; and

Figs. 3 and 4 illustrate diagrammatically specific circuit arrangements for practicing the invention.

With reference to Fig. 1, let *ab* and *cd* be the two circuits required to be balanced, *a*₁ a crosstalk due to capacity unbalance and *C*₁ and *C*₂ balancing crosstalks introduced at the ends of the circuit. Let *B*₁, *B*₂, *B*₃, *B*₄ be the circuit losses in nepers.

Then assuming equal velocities the condition for crosstalk balance from *a* to *d* is that:

$$a_1e^{-(B_1+B_4)} = C_1e^{-(B_3+B_4)} + C_2e^{-(B_1+B_2)}$$

and for crosstalk from *c* to *b*:-

$$a_1e^{-(B_2+B_3)} = C_1e^{-(B_1+B_2)} + C_2e^{-(B_3+B_4)}$$

The solution of these equations is as follows:-

$$C_1 = \frac{a_1 \sinh (B_2 - B_4)}{\sinh (B_1 + B_2 - B_3 - B_4)}$$

$$C_2 = \frac{a_1 \sinh (B_1 - B_3)}{\sinh (B_1 + B_2 - B_3 - B_4)}$$

Since the above expressions only involve differences of attenuation, each unbalance such as *a*₁ can therefore evidently be balanced or represented by two condensers such as *C*₁ and *C*₂ provided that the phase conditions are suitable and that the difference between the attenuations of the circuits does not vary with frequency, so that by suitably choosing the values of the balancing condensers a simultaneous balance of each element of crosstalk is practicable apart from velocity differences.

We can therefore let the complex crosstalk of a repeater section be considered as replaced by two crosstalks *a*₁ and *a*₂ in Fig. 2, *a*₁ need not have the same sign as *a*₂.

Let all four possible readings be taken of the capacity crosstalks necessary to balance the system for the direction of transmission from left to right, i. e.

- (1) Balancing crosstalk *C*₁ between *a* and *c* to balance crosstalk from *a* to *d*.
- (2) Balancing crosstalk *C*₂ between *a* and *c* to balance crosstalk from *c* to *b*.
- (3) Balancing crosstalk *C*₃ between *b* and *d* to balance crosstalk from *a* to *d*.
- (4) Balancing crosstalk *C*₄ between *b* and *d* to balance crosstalk from *c* to *b*.

The conditions of balance will be

$$(1) (a_1 - C_1)e^{-B_2} + a_2e^{-B_1} = 0,$$

$$(2) (a_1 - C_2)e^{-B_1} + a_2e^{-B_2} = 0,$$

$$(3) a_1e^{-B_2} + (a_2 - C_3)e^{-B_1} = 0,$$

$$(4) a_1e^{-B_1} + (a_2 - C_4)e^{-B_2} = 0.$$

From (1) and (3)

$$C_3 = C_1e^{-(B_1 - B_2)}$$

From (2) and (4)

$$C_4 = C_2e^{-(B_2 - B_1)}$$

From (1) and (2)

$$a_2 = \frac{C_2 - C_1}{2 \sinh (B_1 - B_2)}$$

From (3) and (4)

$$a_1 = \frac{C_3 - C_4}{2 \sinh (B_1 - B_2)}$$

Permanent balancing condensers equal and opposite to *a*₁ and *a*₂ are required.

It is thus necessary to determine only three of the quantities *C*₁, *C*₂, *C*₃ and *C*₄ while if the attenuation difference is already known it would be sufficient to determine one of the quantities *C*₁ and *C*₃ and one of the quantities *C*₂ and *C*₄. It is, however, quite possible that

it may be in practice desirable to determine C_1 , C_2 , C_3 and C_4 in order to facilitate testing or calculations or to provide a check.

It will be noted that the readings in the opposite direction of transmission will be duplications of the readings already considered so that the balancing of the cable in one direction will hold good in the opposite direction. Naturally readings of crosstalk balanced at the high level end will correspond in the other direction of transmission with readings of crosstalk balanced at the low level end, with the other circuit considered as the disturbing circuit. Thus a phantom to side reading in the east to west direction balanced at the east end will correspond with the side to phantom reading in the west to east direction balanced at the east end.

Considering a carrier system in which a circuit is used for transmission in both directions, the frequencies used for one direction being different from those used in the other, it would therefore be possible to balance out the far end crosstalk in both directions simultaneously.

So far, no attention has been given to the phases of the individual elements of crosstalk. The phase of the crosstalk current due to a small capacity unbalance between the two circuits is, at the point at which it occurs, exactly 90° out of phase with the voltage at that point, while the magnitude of the current, on circuits of constant impedance, will be proportional to the frequency. Similarly, the voltage induced in the disturbed circuit by a mutual inductance from the disturbing circuit will be exactly 90° out of phase with the current in the disturbing circuit, the magnitude again being proportional to the frequency on circuits of constant impedance. It will be seen from these relations that crosstalk due to capacity unbalance and mutual inductance will be slightly out of phase with one another by an amount equal to twice the angle of the line impedance. Usually, on most types of circuits encountered in practice, this angle is sufficiently small to be neglected for the present purposes, and consequently it may be said that both these types of crosstalk may be eliminated either by inserting capacity unbalance or mutual inductance at the ends of the circuits in the amounts indicated by the above equations. Under certain circumstances however it may be desirable to allow for the phase difference. This may be done in several ways. One way would be to use both mutual inductance and capacity unbalance in balancing, while another and preferred method would be to use two condensers for each balancing operation in conjunction with a phase splitting device which could be made to serve several balancing condensers. Thus in Fig. 4, 1, 2 and 3 are three cable circuits, 4-6 are three-phase splitting devices, 7-9 are terminal equipments and

10-13 are balancing condensers; phase splitter 4 rotates the phase of the currents passing in condensers 11 and 13 by the required amount. Many similar methods are possible.

Resistance unbalance crosstalk on the other hand, leads to crosstalk voltages which are in phase with the inducing current. This type of crosstalk only occurs in the case of phantom to side crosstalk and in this case if the resistance unbalance crosstalk is sufficiently high it may be necessary or desirable to correct it by inserting a small resistance in series with one wire of the side circuit in question.

The importance of making the terminal impedance of the circuit exactly equal to that of the line may be seen from the fact that if a reflected current in the disturbing circuit passes the balancing device it also will cause a crosstalk in the disturbed circuit. This effect will be particularly troublesome if the impedance of the equipment differs from that of the crosstalk set which was employed in balancing the cable.

The degree to which the impedance of the terminating equipment should match that of the line depends on the magnitude of the reduction in far end crosstalk required. Thus if it is required to reduce crosstalk to one-tenth of its original value, then the impedance of the terminal equipment must in general match that of the line within a singing point of $20db$, while if it is required to reduce it to one-thirtieth a singing point of $30db$ is required, and so on. This is a considerably higher standard than has hitherto been considered necessary on four-wire voice frequency circuits, the invention being, of course, not applicable to two-wire circuits. Precautions have been taken to reduce the terminal impedance irregularity on open wire lines used for carrier operation on account of the transpositions being ineffective for reflected currents (see Bell System Technical Journal, October, 1930, page 770 for explanation of this practice). A similar standard of impedance matching is also required on the crosstalk set. This again represents an increase in the degree of matching hitherto considered necessary. A slight impedance unmatched between the line and equipment may however be utilized as a phase splitting device. If it is desired to obtain this effect, the circuit of Fig. 4 could be used, the devices 4, 5 and 6 being in this case attenuating pads having the same impedance as the cable.

The equalization of velocities necessary for practicing the invention can be obtained by several different methods. The equalization of velocities of circuits of a given type, e. g. side circuits, may be carried out by cross-splicing the cable at one or more points within the repeater section in accordance with total capacity and total inductance measurements, or alternatively, velocity measurements which may conveniently be made by

the open circuit, short-circuit impedance method. The splices would be carried out in such a way that upon all circuits of a given type the product of total capacity and total inductance would be as nearly as possible the same.

To control the relative velocity of side and phantom circuits, other devices may be necessary. One method is to vary the average inductance of the phantom coils to give the same average velocity on the phantom circuits as is expected to be obtained on the side circuits. As the phantom to side capacity ratio may vary from 1.58 to 1.7 according to the methods of manufacture of the cable, gauge of conductor and even the cable factory, it will be necessary in certain cases to adopt slightly different inductances for the phantom circuit, according to circumstances. Care is of course normally exercised to insure that the phantom to side capacity ratio remains constant in successive loading sections. Should the average phantom to side ratio depart from the expected value, it may be controlled in the field by the insertion of small amounts of cable having a different lay-up. For example, if the main cable is of quadded, (i. e. multiple twin) type, a small quantity of spiral-4 cable may be included at regular intervals, for instance in every loading section, either in such a way as to convey the speech currents or connected to the main cable by means of a T splice so as to increase the capacity of the section. As the phantom to side capacity ratio of spiral-4 cable is much higher than that of multiple twin cable, it is evident that the loading section phantom to side capacity ratio can be conveniently controlled by this procedure. Another version of this arrangement is to use a much larger amount of spiral-4 cable so that the resulting loading section phantom to side ratio is exactly 2:1 as by this procedure the phantom circuits can be made to have exactly the same velocity and attenuation as the side circuits, so simplifying the balancing of phantom to pair and pair to phantom crosstalk. As almost equal quantities of multiple twin and spiral-4 cable are required for this arrangement, it would be possible to use a cable in which half the quads were of multiple twin construction and half of spiral 4 construction, it being arranged that in any loading section a given circuit would consist of wires laid up according to each construction for exactly half the section.

This scheme has other advantages apart from the questions of balancing, as side and phantom circuits would be capable of use for the same distances so that maximum performance would be obtained for a given cost of cable.

The actual arrangement of the balancing devices at the ends of the circuit will now be

described. In the case of a cable in which no phantom circuits are used, the balancing devices would consist of simple condensers which would be conveniently arranged in a structure of the type shown in Fig. 3.

Spaces 2 are provided upon the rack 3 to accommodate one condenser 4 for balancing the crosstalk between each combination of two circuits. Each cable pair is connected to a pair of horizontal wires such as are indicated by lines 5 and 6 and also a pair of vertical wires such as 7 or 8, so that a condenser may conveniently be connected between two given circuits by connecting one terminal to a horizontal wire and one terminal to a vertical wire, the condenser being placed in a compartment conveniently situated with regard to the intersection of the horizontal and vertical wires.

It is not essential that all circuit combinations should be balanced or that balancing should take place immediately after the installation of the cable. It will, for example, often be convenient to install a cable without special end balancing, merely taking the necessary precautions during installation to insure that all velocities are equal. Subsequently, when a higher standard of performance is required from the cable, the balancing condenser can be added, either from every circuit to every other circuit or, if desired, from each important circuit to every circuit that has appreciable crosstalk to this circuit.

In the case of a quadded cable, a similar device would be used to house the balancing condensers, but it would then be desirable to adopt some special procedure to enable different types of crosstalk to be balanced without interfering with other types of crosstalk. Thus, each condenser may be considered to be replaced by a network of condensers designed to neutralize the unbalance in question without affecting other unbalances. An alternative procedure to this would be to employ simple balancing condensers in conjunction with the normal phantom repeating coil groups. When it is required to balance a crosstalk from a phantom circuit to another circuit, a connection to phantom circuit would be obtained by joining the condenser to the center tap of the side circuit repeating coil. Provided that all pair or pair balancing is carried out before the measurement and balancing of phantom to phantom crosstalk, no interference will be obtained between the functions of the various condensers.

It is known that crosstalk or babble conditions in a cable circuit are greatest if the circuit be situated near the center of the cable. For this reason it is customary to build a cable, comprising both two wire and four wire circuits, with the conductors for the four wire circuits, which are the high quality circuits, occupying the outside layers. (Often the very highest quality circuits are

provided in the center of the cable, but in such case a special screen protects each of these circuits from all other circuits). By adopting the balancing methods set out above such a reduction in babble or crosstalk can be effected on the four-wire circuits that it may be advantageous to adopt a different allocation of the circuits in the cable. According to a feature of the invention therefore, the two-wire circuits of a cable are conductors situated in the outer layers surrounding the conductors of the four-wire circuits, the babble or crosstalk in the latter being balanced by the above described methods. At least three effects are obtained by this rearrangement. In the first place the four-wire circuits of high quality, which unfortunately happen to be the circuits most sensitive to noise, are situated in a region of less noise and interference from outside sources. Secondly, because there are less capacity changes due to cable laying in the outer layers of a cable, the singing point of the two-wire circuits is improved. Thirdly, if screening between conductors of the four-wire circuits transmitting in opposite directions is to be provided, this may be furnished more economically, as the screen need only be placed round a small diameter.

The change over the lay-up of oppositely transmitting conductors of the four-wire circuits may be made at mid-repeater sections on the principle described in the U. S. patent to McCurdy, No. 1,586,633, issued June 1, 1926, or the corresponding British Patent No. 259,546.

In the above description we have been mostly concerned with crosstalk and babble conditions and means or methods for reducing them. It may, however, be possible that other types of disturbance may be reduced by similar or analogous expedients, for example, provided that the velocity of transmission of noise voltages to earth is made the same as that of metallic noise voltages, reductions of noise may be effected by similar means.

What is claimed is:

1. In a transmission system, a communication cable comprising conductors forming two-wire and four-wire circuits, said four-wire circuits being nearer the center of the cable than the two-wire circuits, and means for reducing far end crosstalk between said circuits comprising balancing impedance elements connected between certain of said circuits at the near end of said cable.

2. The method of reducing far end crosstalk between the signaling circuits of a communication cable employing repeaters at the ends thereof, which consists in first equalizing the transmission times of the signaling circuits of a given type by cross-splicing the cable at one or more points within a repeater section to make the total in-

ductance and capacity of said given type circuits substantially the same, and then balancing the far end crosstalk with reactive elements connected between certain of said signaling circuits at the near end of said cable.

3. The method of reducing far end crosstalk between the side and phantom circuits of a quadded communication cable, which consists in first equalizing the transmission times of the side and phantom circuits by suitably adjusting the average inductance of the phantom coils, and then balancing the crosstalk between said circuits by suitable inductances and capacities connected therebetween at the near end of said cable.

4. In a signal transmission system, a quadded communication cable in which substantially half the quads are of multiple twin construction and half of spiral-4 construction so that each signaling circuit comprises alternate lengths of the two constructions, and means for reducing far end crosstalk between the signaling circuits comprising balancing reactive elements of suitable value connected therebetween at the near end of said cable.

In witness whereof, I hereunto subscribe my name this 3rd day of December 1931.

KENNETH E. LATIMER.
